UNITED STATES PATENT OFFICE.

WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

AUTOMATIC TELEPHONE SYSTEM.

Application filed July 15, 1919. Serial No. 311,064.

To all whom it may concern:

Be it known that I, WINFRED T. POWELL, a citizen of the United States, residing at Rochester, in the county of Monroe and 5 State of New York, have invented certain new and useful Improvements in Automatic Telephone Systems, of which the following is a full, clear, concise, and exact description.

10 This invention relates to telephone systems and more particularly to telephone systems employing automatic switches for completing connections between calling and called subscribers.

15 In such systems where automatic or machine ringing is employed to signal called subscribers, the signaling device is always operated in the same manner irrespective of the origin of the call. Very frequently it 20 arises that it is desirable that calls originating from a particular source shall actuate the automatic ringing device to signal the wanted station in a distinctive manner, so that the called subscriber will promptly answer the call. One instance in which such an 25 arrangement will be found to be especially useful, is in the case of calls originating from the substation of a manager or superintendent of an industrial plant who desires 30 that his calls shall be answered with special promptness.

The main feature of this invention is the provision of means to actuate the call signal of a wanted station in a particular manner when the call originates from one source, and to actuate said signal in another manner when the call is initiated from another source.

35 Other features of the invention not specifically enumerated will appear from the detailed description and claims.

The drawing diagrammatically represents 40 a portion of a telephone system in which the present invention is incorporated. The portion of the drawing included within the dotted enclosure at the left, represents a line switch, that is, a switch individual to a line for extending this line to a preselected idle trunk and a master switch for preselecting 45 idle trunks for use. The portion of the drawing at the right of the line included within the dotted enclosure near the center of the drawing, diagrammatically represents a connector switch, and at the lower

right hand corner of the drawing there is 55 shown a ringing machine which is common to a plurality of connector switches in the system of the present invention.

The present invention has been shown in connection with a line switch, that is, a 60 switch individual to the line, for connecting this line to one of a plurality of idle trunks, but it will be understood that any well known selecting means may be employed to extend the calling line to one of a group of 65 connector switches in which the called line terminates.

The line switch shown in the present invention may be of the structure substantially similar to that disclosed in the patent to A. 70 E. Keith, No. 1,151,543, Aug. 24th, 1915, while the connector switch may be of the structure substantially similar to that shown in the patent to Keith, et al., No. 815,176, issued March 13th, 1906. 75

The ringing machine has two interrupters mounted on a constantly rotating shaft. These interrupters or commutators are provided with a plurality of conducting segments, one of them being provided with four 80 conducting segments, and the other with two conducting segments for interrupting the source of ringing current in a distinctive manner.

With this brief description of the apparatus employed, it is believed that the invention will best be understood by describing the method of establishing a connection from a calling substation A, which we will assume is that of a manager or superintendent, to the called substation B. Since 85 the call originates from a substation which requires prompt response, distinctive ringing current will be supplied to the called substation B in a manner to be described. 90

In initiating a call, the subscriber at A removes his receiver from its switchhook whereupon the slow releasing line relay LR is energized over a circuit extending from grounded battery, winding of the line relay 100 LR, outer left hand back contact and armature of the relay 2, tip conductor 3 of the calling line, through the calling substation circuit, ring conductor 4, and inner armature and back contact of relay 2, to ground. 105 Line relay LR is energized in this circuit and closes a circuit through the left hand winding of relay 2, which attracts its arma-

ture, causing the plunger 5 to bring the contacts of the calling line and an idle trunk into engagement. The operation of the plunger 5 besides closing the line and trunk contacts, 5 causes contact 6 to extend ground to conductor 7 for a purpose to be described, and causes the spring 8 to close a break point in the test circuit. As soon as the calling line is connected to the idle trunk disclosed, the stepping relay SR is energized over a circuit completed through the two sides of the 10 trunk and calling line in series. The stepping relay SR attracts its armature to close a circuit for the slow releasing relay 9 in the well known manner. This relay 9 is so 15 adjusted that it does not retract its armatures when its energizing circuit is momentarily interrupted, but responds only to a long interruption of this circuit. At the left 20 hand armature and front contact of the relay 9, when attracted, ground is connected to the test conductor 11 which serves as a guarding potential to prevent the seizure of the calling line by any connector. This ground is 25 also connected through spring 8 to maintain energized the right hand winding of relay 2 which serves to hold the plunger 5 actuated until the time of release. This same ground is also effective to operate the master 30 switch to preselect an idle trunk for the next call to be originated in a manner disclosed in the above mentioned line switch patent.

The connector switch is now in condition to be directly operated in response to impulses transmitted from the dial of the calling substation. In response to each of these 35 impulses, corresponding to the tens digit of the wanted number, the stepping relay SR operates its armature and at its back 40 contact closes a circuit from ground, armature and front contact of relay 9, slow-releasing relay 10, winding of the primary motor magnet PM, side switch wiper 11 in its first position, to grounded battery. In 45 response to each closure of this circuit, the primary motor magnet is operated and advances the connector switch one step in its group selecting movement. The slow-releasing relay 10 is energized in the circuit just 50 described, and is maintained energized until the closing of the tens series of impulses, and thus completes an energizing circuit for the escape magnet ESC, from grounded battery, resistance, winding of this magnet, 55 continuity spring and armature of slow-releasing relay 10, to ground. At the close of the tens series of impulses, the slow-releasing relay 10 retracts its armature and 60 opens the energizing circuit of the escape magnet ESC, just described, causing this magnet to move the side switch wipers into their second position.

In response to the operation of the dial at the substation A corresponding to the 65 units digit of the wanted number, the step-

ping relay SR again vibrates its armatures, but in this instance it controls the secondary magnet SM, over a circuit traceable from grounded battery, side switch wiper 11 in its second position, winding of the secondary 70 magnet, outer right hand back contact and armature of the test relay TEST, winding of the slow-releasing relay 10, right hand front contact and armature of relay 9, back contact and armature of relay SR to ground. 75 In response to the first closure of this circuit just described, the escape magnet ESC is operated over the circuit previously described as extending from grounded battery, resistance, winding of the escape magnet ESC, continuity spring and armature of relay 10, to ground. In response to each retraction of the armature of the stepping relay SR, the secondary motor magnet SM is operated to advance the connector switch 80 in the group of lines previously selected during the group selecting movement.

At the present stage of the description it will be assumed that the wanted line is idle. Under this assumption at the close of the 90 units series of impulses, the relay 10 will retract its armature and thus interrupt the operating circuit of escape magnet ESC, causing this magnet to move the side switch wipers into their third or signaling position. 95

In accordance with the present invention, means are provided in the case of calls originating in one group of lines to signal a called station in a distinctive manner. This means comprises two interrupters generally designated 12 and 13. The interrupter 12 has twice as many segments as the interrupter 13, and thus the ringing and silent intervals on this portion of the ringing machine are shorter and alternate more rapidly than in the case of the interrupter 13. A relay 14 is provided for connecting either the interrupter 12 or 13 in the signaling circuit, depending on the origin of the call. 100

It was assumed earlier in the description that the call originated at the station of the party requiring an especially prompt response to his calls. In this case the spring 6 corresponding to his line at his line switch is connected to ground, so that when the plunger 5 operates, a circuit was extended from ground, through the spring 6 and its contact, conductor 7, and winding of the relay 14, and when the side switch wiper 11 reaches its third position, this circuit is completed to grounded battery. Relay 14 is energized in this circuit, and closes a signaling circuit from grounded battery, resistance, generator 15, interrupter 12, front contact and armature of relay 14, winding of the trip relay TRIP, side switch wiper 16 in its third position, connector brush 17, through the called subscriber's line and substation circuits, connector brush 18, side 115 120 125 130

switch wiper 19 in its third position, to ground. The bell at substation B is thus operated in a distinctive manner. At the time when the side switch wipers were 5 moved into their third position, the escape magnet ESC was energized in a circuit traceable from grounded battery, resistance, winding of the escape magnet ESC, side switch wiper 20 in its third position, to 10 ground. The escape magnet ESC is maintained energized in this circuit until the called party responds, whereupon the marginal trip relay TRIP, is energized in the well known manner, and attracts its armature. 15 The escape magnet ESC is thus short circuited by a ground at the armature of the trip relay TRIP and deenergizes to move the side switch wipers into their fourth or talking position. Guarding potential is supplied 20 to the test terminal of the wanted line from ground, side switch wiper 21 in its fourth position and connector test brush 22. Talking battery is supplied to the calling subscriber through the windings of the 25 stepping relay SR, while talking battery is supplied to the called subscriber through the windings of the impedance coil 23.

If the call had originated at some substation which is not entitled to this special 30 service, the spring 6 of the line switch of this line would not be connected to ground, so that when the side switch wiper 11 moved into its third position, no operating circuit would be completed for the relay 14 and 35 signaling current would be supplied to the wanted station through the interrupter 13 with the resulting operation of the bell at the called station in the ordinary intervals of ringing and silent periods.

40 Let it be assumed that the wanted line is busy when the connector brushes 17, 18 and 22 are placed in engagement with its multiple terminals when the slow-releasing relay 10 deenergized at the close of the units series 45 of impulses, a substituted operating circuit for the escape magnet ESC is then completed from grounded battery, winding of the escape magnet ESC, continuity spring and contact of relay 10, winding of the test 50 relay TEST, continuity spring and contact of this relay, side switch wiper 21 in its second position, test brush 22 of the connector through a multiple terminal of the wanted line, through a test brush corresponding to 55 21 in its third or fourth positions to ground at the connector which has seized the called line. The test relay attracts its armatures and at its inner right hand armature and continuity spring closes a locking circuit for 60 itself to ground through the off normal contact and spring 23. At the left hand armature and front contact of the test relay, a circuit is closed for applying a busy tone to the calling line from the busy machine BZ.

65 When the calling subscriber replaces his

receiver on its switchhook, the energizing circuit of the stepping relay SR is interrupted, and shortly after this the slow-releasing relay 9 retracts its armatures. At the right hand armature of this relay a circuit is closed for the release magnet REL of the connector, from grounded battery, winding of this magnet, off normal spring and contact 24, back contacts and armatures of relays 9 and SR, to ground. The releasing magnet REL operates in the well known manner to restore the brushes and apparatus of the connector to normal position. At the left hand armature and front contact, the holding circuit for the relay 2 extending over conductor 11 is interrupted and permits the plunger 5 to be withdrawn from the contact bank, and in due course of time the plunger is placed under the control of a master switch to be positioned before terminals of idle trunks. The apparatus is now in condition for completing successive calls.

While no selector switches have been disclosed in the present showing, it will be readily understood that if the invention is incorporated in larger systems such switches will be employed.

What I claim is:—

1. In an automatic telephone system, a plurality of subscribers' lines of different classes, means including final connector switches for interconnecting said lines, a single trunk terminating at each of said switches, a signaling device associated with each subscriber's line, and means for discriminating in which class of lines a call originates for variably operating said signaling devices.

2. In an automatic telephone system, a plurality of telephone lines, each of said lines being provided with a signaling device, means including automatic switches for interconnecting said lines of different classes, a single trunk extending to each automatic switch, two sources of signaling current of different character, and means for discriminating in which class of lines a call originates for selecting signaling current of the proper character.

3. In a telephone exchange system, subscribers' lines, a signal associated with each line, an automatic switch wherein said lines terminate, a single trunk terminating at said switch, means for causing said switch to select a line, and means automatically operated by the selection of one of said lines for variably operating the signal thereof.

4. In a telephone exchange system, subscribers' lines, a connector in which said lines terminate, a single trunk terminating at said connector, means for causing said connector to select a desired line, sources of signaling current of different character, a relay automatically operated by the seizure

of said trunk for selecting signalling current of the proper character.

5. In a telephone exchange system, subscribers' lines of different classes, a signal associated with each line, a connector in which said lines terminate, a single trunk line terminating at said connector, means for setting said connector on said lines over said trunk, a signalling circuit associated 10 with said connector, a relay at said connector controlled by the character of the calling subscriber's line, to control said signalling circuit, and sources of current of different character controlled by said relay.

15. 6. In an automatic telephone system, a plurality of telephone lines of different classes, means including automatic switches for interconnecting said lines, signalling devices associated with each of said lines, 20 two sources of signalling current of different characteristics and means controlling the application of said sources of signalling current to said signalling devices and a circuit independent of the talking conductors of 25 said telephone line over which said means is controlled.

7. In an automatic telephone system, a plurality of telephone lines of different classes, means including automatic switches 30 for interconnecting said lines, signalling devices associated with each of said lines, two sources of signalling current of different character and a relay controlling the application of said sources of signalling 35 current to said signalling devices and a circuit independent of the talking conductors of said telephone lines over which said means is controlled.

8. In an automatic telephone system, a 40 plurality of telephone lines, means including automatic switches for interconnecting said lines, signalling devices on each of said lines, two sources of signalling current associated with certain of said automatic 45 switches and means arranged to be automatically controlled from the calling line independent of the talking conductors of said line to apply one or the other of said

sources of signalling current to a wanted line.

9. In an automatic telephone system, a plurality of telephone lines, signalling devices thereon, means including non-numerical and numerical automatic switches for interconnecting calling and wanted telephone lines, two sources of current of different character associated with said numerical switches for operating said signalling devices and means controlled over a circuit extending through a non-numerical switch but independent of the talking conductors of the calling telephone line for applying signalling current of the desired character.

10. In an automatic telephone system, a plurality of telephone lines of different classes, each provided with a signaling device, a group of trunks, a group of connector switches, each trunk terminating in a connector switch, a single group of trunk selecting switches individual to said group of trunks, means including a trunk selecting switch and a connector switch for interconnecting calling and called telephone lines, and means for discriminating in which class of lines the call originates for variably operating said signaling device.

11. In an automatic telephone system, a plurality of telephone lines of different classes, a signal for each telephone line, means including a connector switch for interconnecting said lines, a trunk circuit, a single pair of conductors bridged to the incoming end of said trunk, an impulse relay connected to said bridged conductors for controlling the operation of said connector switch, two sources of current of different character and means for discriminating in which class of lines the call originates for selecting signaling current of the proper character to operate the signal of a called line.

In witness whereof, I hereunto subscribe my name this 14th day of July A. D. 1919.

WINFRED T. POWELL.
